UNITED STATES PATENT OFFICE.

FRANK DASZYNICR KULCZYCKE, OF WOODLAWN, PENNSYLVANIA.

PICKLING APPARATUS.

Application filed May 28, 1923. Serial No. 642,069.

To all whom it may concern:

Be it known that I, FRANK D. KULCZYCKE, a citizen of the United States, and a resident of Woodlawn, in the county of Beaver and State of Pennsylvania, have invented certain new and useful Improvements in Pickling Apparatus, of which the following is a specification.

My present invention relates generally to the pickling of tinned plate as well as tinned articles of various characters, and more particularly to an apparatus for this purpose, my primary object being the provision of a continuous apparatus by which the pickling of articles may be carried out quickly and effectively in a manner to be presently described in connection with the accompanying drawings which show the preferred construction of my invention and which form a part of this specification.

In these drawings,

Figure 1 is a top plan view of my improved apparatus,

Figure 2 is a side elevation thereof, and

Figures 3 and 4 are respectively detail fragmentary views in top plan and side elevation of portions of the carrier.

Referring now to these figures my invention proposes an apparatus including a frame having side uprights 10 and 11 rigidly upstanding at the ends of the frame and side uprights 12 similarly upstanding centrally between the end uprights 10 and 11, the end uprights 10 and 11 supporting bearings for end cross shafts 13 and 14 and the central uprights 12 supporting at their upper ends bearings for a central cross shaft 15 and also supporting brackets 16 having bearings for a transverse crank shaft 17.

Above the ground rails 18 to which the lower ends of the uprights 10, 11 and 12 are securely fastened, these uprights are connected by longitudinal side rails 19, the latter supporting tanks 20 and 21 upon opposite sides of the central uprights 12 and opening upwardly in the spaces between these central uprights and the end uprights 10 and 11, the tanks being respectively the acid and water tanks for a purpose which will be presently described.

Suspended within the tanks 20 and 21 are a pair of slatted platforms 22 and 23 to whose opposite ends are pivotally connected as at 24 the lower ends of hangers 25. The upper ends of these hangers 25 are

pivotedly connected as at 26 to spaced points of the side arms 27 of a walking beam having central bearing upon the central cross shaft 15 whereby in the swinging movement of the walking beam the platforms 22 and 23 will be alternately raised and lowered in the tanks 20 and 21.

The side arms 27 of the walking beam are inclined with respect to one another upon opposite sides of the center of the walking beam and are braced by truss rods 28 adjustably connected by central turnbuckles 29 and extending between the outer ends of the arms over struts 30, one of the arms 27 at each side of the walking beam being movably connected by a pitman 31 with one of the cranks 32 of the crank shaft 17 before mentioned.

On the end shafts 13 and 14 are mounted enlarged sprockets 33 and 34 around which an endless flexible carrier 35 travels. The upper run of this carrier also travels centrally thereof over a small sprocket 36 on the central transverse shaft 15 between the side arms 27 of the walking beam, the portions of this upper run of the chain upon opposite sides of the sprocket having sufficient slack to dip into the tanks 20 and 21 in which these portions of the carrier are supported upon the slatted platforms 22 and 23 and are shifted vertically with the rise and fall of these platforms in operation.

For the above purposes the carrier 35 is formed of a series of parallel cross rods 35^a as best seen in Figures 3 and 4, extending through elongated open connecting links 37 the latter of which are spaced apart by thimbles 38 on the rods so that those portions of the carrier which dip into the tanks may rise and fall without buckling to an undesirable extent.

Each of the several open connecting links 37 has upright article holding pins 39, and the carrier as a whole is in this way equipped to effectively support sheet metal articles of various characters and metal plate fed to the carrier at one end of the apparatus for successive passage through the acid and water tanks 20 and 21 and discharged from the other end, it being obvious that in the course of the passage of the various articles in the tanks 20 and 21, these articles will not only be moved lengthwise of the tanks through the liquid therein, but will also be shifted up and down

during their passage through the liquid so as to insure action of the liquid upon all portions of the surfaces of the articles.

Any suitable power may be utilized for the movement of the parts, connected for instance to one or both of the end shafts 13 as well as to the crank shaft 17, and it is obvious that with the shafts 13, 14 and 17 driven as described the carrier will move continuously with its load of articles to be pickled, successively through the tanks 20 and 21 and that during this movement those portions of the carrier within the liquid of the tanks will be raised and lowered by virtue of their movement across the platforms 22 and 23 having continuous alternate up and down movement by virtue of their suspension from the ends of the walking beam.

The apparatus as proposed by my invention is not only simple and inexpensive when its capacity in results are taken into consideration, but is economical in its upkeep, strong and durable in use and effective and efficient for the intended purposes.

I claim:

1. A pickling apparatus including spaced apart upwardly opening fluid tanks, sprockets between and beyond the tanks in line therewith, an endless flexible carrier extending around the end sprockets and having its upper run traveling over the central sprocket and dipping between the central and end sprockets into the said tanks, vertically shiftable platforms within the tanks and upon which the dipping portions of the carrier travel, a walking beam from which the said platforms are suspended, and means for oscillating the said walking beam whereby to raise and lower the platforms and the dipping portion of the carrier as the latter pass through the tanks.

2. A pickling apparatus including spaced apart upwardly opening fluid tanks, sprockets between and beyond the tanks in line therewith, an endless flexible carrier extending around the end sprockets and having its upper run traveling over the central sprocket and dipping between the central and end sprockets into the said tanks, vertically shiftable platforms within the tanks

and upon which the dipping portions of the carrier travel, a walking beam from which the said platforms are suspended, and means for oscillating the said walking beam whereby to raise and lower the platforms and the dipping portion of the carrier as the latter pass through the tanks, said carrier being formed of a series of open links and cross rods passing through the links whereby to permit their dipping portions to flex vertically without buckling.

3. A pickling apparatus including spaced apart upwardly opening fluid tanks, sprockets between and beyond the tanks in line therewith, an endless flexible carrier extending around the end sprockets and having its upper run traveling over the central sprocket and dipping between the central and end sprockets into the said tanks, vertically shiftable platforms within the tanks and upon which the dipping portions of the carrier travel, a walking beam from which the said platforms are suspended, and means for oscillating the said walking beam whereby to raise and lower the platforms and the dipping portion of the carrier as the latter pass through the tanks, said carrier being formed of a plurality of flexibly connected relatively movable links having upstanding article holding pins for the purpose described.

4. A pickling apparatus including spaced apart upwardly opening tanks, an endless flexible carrier having article holding means and having its upper run movable across the tanks and arranged to dip into the said tanks, vertically shiftable members in the tanks on which the dipping portions of the carrier travel, and means for continuously shifting said members up and down during travel of the carrier as described.

5. A pickling apparatus including upwardly opening tanks, an endless carrier arranged to travel across the tanks and to dip into the same, and means in movable engagement with the carrier and located within the tanks for shifting the dipping portions of the carrier up and down continuously during movement of the carrier through the tanks.

FRANK DASZYNICR KULCZYCKE.
